UNITED STATES PATENT OFFICE.

JOHN H. FRY, OF GRAND RAPIDS, MICHIGAN.

LAWN-SPRINKLER.

SPECIFICATION forming part of Letters Patent No. 572,000, dated November 24, 1896.

Application filed August 27, 1895. Serial No. 560,680. (No model.)

To all whom it may concern:

Be it known that I, JOHN H. FRY, a citizen of the United States, residing at the city of Grand Rapids, in the county of Kent and State of Michigan, have invented certain new and useful Improvements in Lawn-Sprinklers, of which the following is a specification.

This invention relates to lawn-sprinklers or hose-nozzles, and has for its object to provide novel, simple, efficient, and economical means whereby it is possible to spread the stream issuing from the mouth of the nozzle and spray the water to a greater or less extent without stopping the flow of the water to or interrupting the discharge of the water from the nozzle.

Figure 1 shows a longitudinal sectional view of a nozzle containing my spraying device on a line through the central opening of the nozzle. Fig. 2 shows a front elevation or front view of the spraying device and nozzle, with the nozzle raised at an angle of about forty-five degrees in order to show the hood and the relative position of the spraying device and the opening.

Similar letters refer to similar parts throughout both views.

A represents the nozzle proper, provided with an opening B, through which the water is discharged.

C represents a hood at the front end of the nozzle, which is intended to prevent the water from rising too high or spreading too wide. The hood is open or cut away at one side.

In the example of my invention shown in the drawings I have shown four fingers, (indicated by E, F, G, and H.) The spraying-fingers are all mounted on a single bolt J. This bolt may be screw-threaded and engage with a screw-thread in the nozzle, or it may be permanently attached to the nozzle and provided with a nut for retaining the spraying-fingers in place. Upon this bolt the arms are adapted to rotate. When it is desirable to use the nozzle without the operation of the spraying-fingers, the fingers can be turned so that the opening B will be between two of the fingers and the water will then pass off freely without coming in contact with the fingers.

When it is desired to use my invention for sprinkling streets, where the stream should

be but little spread, I use the narrow finger E. If I desire to spread it more I use the finger H, and if I desire to obtain the greatest amount of spreading surface, in order to carry the water to a finer spray, I use the broader finger G. It will be noted that a less number and a greater number than four fingers might be used in this rotary spraying device, but I deem four preferable, for the reason that there is greater room between the fingers for the round stream than there would be if a larger number of fingers were used, and the use of the four fingers of different sizes or widths will allow of the use of a greater variety of sprays than if a less number of fingers were used.

In order that the water when striking the fingers will not flow backward or will not be thrown backward, so as to drip from the spraying-fingers, I prefer to make them angular or rounded on their upper surface. I have found by actual experiment that the flat upper surface to the spraying-finger was not desirable. The water striking with considerable force against the flat surface has a tendency to flow backward, so as to drip from the end of the nozzle. I also prefer to cut out the lower part of the fingers in order to save materials. However, this structure is not necessary to the operation of my invention. In Fig. 1 I have shown a screw-thread D in the nozzle, which screw-thread is for the purpose of attaching the nozzle to the hose.

I have also shown a spike P, which is useful in attaching the nozzle to the ground when it is desirable to sprinkle a long time in a single place.

In the use of an ordinary nozzle when it is desired to spread the water issuing therefrom the person holding the nozzle places a finger, usually the forefinger, over the end of the nozzle, and according to the pressure applied the stream of water is more or less spread. By my invention it is unnecessary to place the finger over the nozzle, while the pivoted fingers of different width secure the necessary changes in the spread of the stream in a very effective manner.

Having thus described my invention, what I claim to have invented, and desire to secure by Letters Patent, is—

The combination with a nozzle, of a pivot

projecting from the side of the nozzle, and a spraying device mounted on said pivot and composed of a plurality of flat imperforate fingers of different widths which radiate from 5 the pivot in the same flat plane inclined with relation to the longitudinal axis of the nozzle, said spraying device being rotatable on the pivot to place any one of the fingers of different widths in an inclined plane in the path 10 of the stream flowing through the nozzle, or to place any two of said fingers upon each

side of said nozzle to permit an unobstructed flow of water from the nozzle between them, substantially as described.

In witness whereof I have hereunto set my 15 hand and seal in the presence of two witnesses.

JOHN H. FRY. [L. S.]
